UNITED STATES PATENT OFFICE

GEORGE D. WILKINSON, OF OAK PARK, AND ELMER D. PELLEGRIN, OF DES PLAINES, ILLINOIS, ASSIGNORS TO CRIBBEN & SEXTON COMPANY, OF CHICAGO, ILLINOIS, A CORPORATION OF ILLINOIS

DESIGN FOR A RANGE

Application filed March 21, 1932. Serial No. 43,256. Term of patent 7 years.

To all whom it may concern:

Be it known that we, GEORGE D. WILKINSON, a citizen of the United States, residing at Oak Park, in the county of Cook, State of Illinois, and ELMER D. PELLEGRIN, a citizen of the United States, residing at 724 Arlington Avenue, Des Plaines, in the county of Cook, State of Illinois, have invented a new, original, and ornamental Design for a Range, of which the following is a specification, ref-

erence being had to the accompanying drawing, forming a part thereof, in which:

Figure 1 is a perspective view of the range with the top closed; and Fig. 2, a similar view of the range with the top raised.

We claim:

The ornamental design for a range as shown.
